UNITED STATES PATENT OFFICE

2,606,462

SAW VISE

Fred O. Queel, Cresco, Iowa

Application July 20, 1950, Serial No. 174,942

1 Claim. (Cl. 76—78)

1

This invention relates to new and useful improvements in saw vices.

One object of my invention is to provide a novel saw vice, which is long enough to accommodate a carpenter's saw, full length, and will also handle a two-man cross cut saw and band saws, that is to say, may be used in connection with any form of saw, except circle saws.

A further object of my invention is to provide a saw vice in which the loose or pivoted jaw may be actuated and moved into closed or saw engaging position, with the use of one operating lever and cam shaft.

A still further object of my invention is to provide novel means for fastening the stationary jaw of the vice to a bench and for hingeing the pivoted jaw to a shaft carried by the frame of the latter.

Still another object of my invention is to provide a saw vice that is relatively simple and economical in construction and highly efficient and durable in use.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a front elevation of a saw vice, embodying my improvements.

Figure 2 is a top plan view.

Figure 3 is a horizontal section, taken on line 3—3 of Figure 1.

Figure 4 is an end view.

Figure 5 is a vertical transverse section, taken on line 5—5 of Figure 2.

Figure 6 is an enlarged detail transverse section, taken on line 6—6 of Figure 3.

Referring to the drawings for a more particular description of my invention, and in which drawings like parts are designated by like reference characters throughout the several views, A designates the pivoted jaw of the vice, which is disposed at the front of the latter, for the convenience of the operator, and B the stationary jaw which is disposed at the rear or bench side of the device.

The stationary jaw B comprises the jaw proper, designated by the numeral 1, of V-shape form in cross section, with the flat top member a of the jaw proper disposed at an upward inclination and

2

formed with the beveled saw engaging edge b and with the lower member c thereof disposed at a downward and inward inclination.

Perpendicular angle iron legs 2 are welded at their upper ends to the face and bottom edge of the lower member c of the stationary jaw proper, and an angle bar 3 is welded at opposite ends to the aforesaid legs 2, as a means of fastening the stationary jaw to a bench.

In carrying out my invention, the pivoted jaw A of the vice, comprises a jaw proper 4, of V-shape form in cross section, and otherwise similar in form to the stationary jaw 1, while perpendicular angle iron legs 5 are welded at their opposite ends to opposite ends of the former. A horizontal reinforcing cross bar 6, extends between the legs 5 of the pivoted jaw A, the purpose of which will be apparent.

Upright angle iron supports 8 are arranged with their transverse members 9 fitting against the corresponding transverse members 10 of the perpendicular legs 5, and with the lower ends of their other members, as 11, welded to the bearing blocks 12, which fit between the members 11 and the corresponding members 13 of the angle iron legs 2.

A horizontal cam shaft 14 is arranged with its opposite ends journaled in the bearing blocks 12 and is provided adjacent opposite ends, with the cylindrical cams 15, which are eccentrically mounted on said cam shaft and work against the lower ends and inner faces of the members 11a of the angle iron legs 5 of the pivoted jaw.

An operating lever 16 is suitably fastened at its inner end to the center of the cam shaft 14 and its upward swinging movement described in closing the vice, is limited by the angle bar 3. The upper ends of the perpendicular angle iron legs 5 are hinged to opposite ends of a horizontal shaft 17, which extends through the transverse members 10 of the former and the transverse members 9 of the angle iron supports 8.

In practice, the saw to be filed is securely clamped between the stationary and pivoted jaws of the vice merely by swinging the free end of the operating lever 16 upwardly into raised position against the angle bar 3, during which operation the cams 15 work against the lower ends and inner faces of the members 11a of the upright legs 5 of the pivoted jaw A and swing them outwardly to the desired extent with the shaft 17 acting as the fulcrum.

From the foregoing description taken in connection with the drawings, it is thought that the construction, operation and advantages of my in-

vention will be readily understood, without requiring a more extended explanation.

Various changes in the form, proportions and minor details of construction may be resorted to without departing from the principle or sacrificing any of the advantages of my invention, as defined in the appended claim.

It is to be understood that the vice may be constructed of metal or any other suitable material found practical for the purpose.

Having described my invention, what I claim as new and desire to secure by Letters Patent, is:

A saw vice of the character specified, comprising a stationary jaw, consisting of an upper jaw proper of V-shape form in cross section, perpendicular angle iron legs fastened at their upper ends to the stationary jaw, an angle bar secured at opposite ends to said perpendicular legs for attaching the stationary jaw to a bench, a pivoted front jaw, consisting of an upper jaw proper of a form corresponding to that of the jaw proper of the stationary jaw, perpendicular angle iron legs secured at their upper ends to the jaw proper of the pivoted jaw, upright angle iron supports fitting against said last mentioned legs, bearing blocks fitting between and welded to the lower ends of the legs of the stationary jaw and the supports of the pivoted jaw, a cam shaft journaled at opposite ends in said bearing blocks, cams ecc-

centrically mounted on opposite ends of said cam shaft, and working against the corresponding members of the angle iron legs of the pivoted jaw, a hand lever carried by the cam shaft for closing the pivoted jaw of the vice, a re-inforcing cross bar secured at opposite ends to the legs of the pivoted jaw and serving as a stop to limit the upward swinging movement of the latter, and a second shaft arranged with opposite ends extending through said upright angle iron supports and serving as a fulcrum for the pivoted jaw in closing and opening the vice.
